ELECTRICALLY HEATED WEARING APPAREL

Gerrit Van Daam, Buffalo, N. Y.

Application February 20, 1943, Serial No. 476,553

5 Claims. (Cl. 219—46)

1

This invention relates to electrically heated wearing apparel, and more particularly to garments or suits and accessory wearing apparel to be worn by aviators and may also be embodied in garments or suits and accessory wearing apparel to be worn by divers and others subjected to low temperatures. The principal object of the invention is to provide new and improved wearing apparel of these types.

The novel features of the invention will appear from this specification and the accompanying drawings, showing several embodiments of the invention, and forming a part of the specification, and all of these novel features are intended to be pointed out in the claims.

In the drawings:

Figure 1 is a front elevation of a garment embodying the invention, to be worn by an aviator, for example, the fabric part of the garment and the belt means therefor being omitted, but indicated in broken outline, in order to more clearly show the arrangement of the electric heating means and the conductor means for feeding the heating means with electric current.

Figure 2 is a section taken on the line 2—2 of Figure 1, the fabric wall of the garment being here shown in section, along with belt means for the garment.

Figure 3 is a fragmentary sectional view taken on the line 3—3 of Figure 2, considerably enlarged.

Figure 4 is a partly broken plan view, on a larger scale than Figure 1, of an electrically heated innersole means for heating a foot of a wearer of the garment shown in Figure 1.

Figure 5 is a section taken on the line 5—5 of Figure 4.

Figure 6 is a fragmentary view partly in section, taken on the line 6—6 of Figure 1.

Figure 7 is an elevational view, on a larger scale than Figure 1, of the palm side of a mitten for heating the left hand of the wearer of the garment shown in Figure 1.

Figure 8 is a fragmentary sectional view, on a larger scale, taken along the line 8—8 of Figure 7.

Figure 9 is an electrical diagram of the circuits corresponding to the embodiment shown in Figure 1, and

Figure 10 is a fragmentary electrical diagram of the circuits of another embodiment.

Referring more particularly to Figures 1, 2, and 3 a belt 20 is provided which may be made of fabric or any other suitable material, the belt being here shown as provided at one end with a buckle 21 having a tongue 22 adapted to co-

2

operate with holes 23 in the other end of the belt. It will be understood of course that means for detachably joining the ends of the belt may assume any other desired and suitable form. The 5 longitudinal margins of the belt are stitched as by stitching 24 (Figure 3), or otherwise suitably fastened, to the waist portion of the garment so that the longitudinal center portion of the belt and the opposite adjacent portion g' of the garment 10 may be moved away from each other thereby to provide conduit means 26 in which bus conductor means 25 may be inserted. The stitching 24 hereinbefore referred to may terminate a desired distance short of the buckle end of the belt 20, and a desired distance short of the cooperating, other end of the belt, so that the buckle and the cooperating, other end are free of the garment for desired lengths as indicated in Figure 2. The bus conductor means 25 disposed 15 within the conduit means 26 provided by the belt 20 as hereinbefore described, is electrically connected, in this instance, to conductor means here shown as a two-conductor cable 27 of any desired length provided at the free end thereof with a plug 28 adapted for insertion in a socket 29 (Figure 9) connected to line wires 30 from a source of electricity. If desired, a line switch 120, and a rheostat 121 may be interposed in the line wires 30. In general, reference may be had 20 to Figure 9 for the electrical connections of the embodiment of Figure 1. The cable 27 may be supported by a bracket 31 carrying a clamp 32, the bracket being suitably fastened to the belt 20, and the arms of the clamp 32 serving to hold 25 the cable 27 relatively to the belt.

The bus conductor means 25 has a portion 33 which runs clockwise, as viewed from above the belt 20, in the conduit means 26 provided by the belt from the place where the cable 27 enters the belt, to a switch 34 which is carried by the belt 20 and is interposed in the bus conductor means 25 so as to be adapted to complete or interrupt the current supply to the electrical heating means provided in the garment (see Figure 9). If desired electrical outlet means 35, here shown as a two pole socket, may be mounted on the belt 20 and electrically connected in parallel to the bus conductor means 25, for purposes to be described.

The bus conductor means 25 disposed within 40 the conduit means 26 provided by the belt 20 also has a portion 36 which extends in a counter-clockwise direction from the place where the cable 27 enters the belt 20, around the back to the wearer's right side.

55 Whatever heating means is provided for the

garment is fed by suitable connections to the bus conductor means 25, each heating means being connected in parallel with the bus conductor means. In the instance shown in Figure 1 there is provided a belt-like electric heating means 37 for heating the chest and back of the body of the wearer of the garment, the terminal end margins 38, 39 of this belt-like heating means being here shown as disposed adjacent the longitudinal split (indicated by the broken line 40 in Figure 1) in the anterior wall of the garment. The belt-like heating means 37 is thus adapted substantially to encircle the chest and back of the wearer leaving only a slight gap, if any, in the front. The longitudinal split 40 in the garment, which may extend from the neck to the crotch of the garment if it is of the coverall type, may be closed by a closure means 41 of the interlocking-element slide-operated type, or by buttons or any other suitable closure means.

A conductor cable 42 comprising two conductors connected respectively to the conductors of the portion 36 of the bus conductor means 25 serves to feed with the current the belt-like chest and back heating means 37.

The ends of the belt-like heating means 37 may be fastened to the inside of the garment so that these ends are adjacent the longitudinal split, by a desired number of snap fasteners 43 or in any other desired suitable way. One of these snap fasteners, 43, is shown in side elevation in Figure 6, the socket part 43a of the snap fastener being, in this instance, mounted on the fabric wall portion g' of the garment and the plug part 43b being mounted on the heating means 37. The heating means 37 is here shown as in the form of a heating pad comprising a suitably insulated resistor 45 which is disposed between two walls 46, 47 of wool fabric or any other suitable insulating material, these walls being shown in Figure 6 as partly broken away at the top to show a part of the resistor 45. The wool walls 46, 47 are desirably slightly larger than the area of the insulated resistor 45 and the overlapping margins may be fastened together by stitching 48 or in any other suitable way. It will of course be evident that the belt-like heating means 37 is assemblable with and separable from the garment as a unit. If desired the heating means 37 may be fastened to the garment by fasteners at other additional points of its circumference.

It will be evident that the circumferential length of the heating means 37 may be so selected, or the fastener parts 43a and 43b so located, or both, that when the closure means 41 is closed, the heating means 37 is put under tension sufficient so that the heating means is maintained snugly encircled about the back and chest of the wearer, and hence in heat-conducting relation to the back and chest, even though the garment itself may fit the wearer loosely. The snugly encircling effect of the heating means 37 is enhanced if this heating means is at least somewhat extensible and contractible, which it is in this instance, because at least the covering comprising the walls 46, 47, to which the fastener parts 43a are attached, is resiliently extensible and contractible.

Electrically connected to the conductors of the portion 36 of the bus conductor means 25 is conductor means which may be a two conductor cable 49r. The cable 49r passes through an aperture 50 in the wall portion g' of the garment, up-

wardly inside of the garment and passes over the right arm pit of the garment into and along the inside of the right hand sleeve 51r. The cable 49r is here shown as extending beyond the terminal end of the sleeve 51r, and the end of the cable is provided with any suitable insulating supporting means 53 for supporting a pair of connector terminals 52 to which the conductors of the cable 49r are respectively electrically connected. The connector terminals 52 may be of the snap fastener type or any other type affording easy attachment and detachment from complementary connector terminals on a glove or mitten (Figure 7) containing electric heating means for heating the hand of the wearer.

Conductor means which may be in the form of a cable 54r is electrically connected to the portion 36 of the bus conductor means 25 at approximately the same place as the cable 49r, but extends downwardly into and along the inside of the right hand leg 55r of the garment. As here shown the lower end of the cable 54r carries any suitable insulating means 56 for supporting a pair of connector terminals 57 adapted to cooperate with complementary connector terminals on a heating means (similar to Figure 4) for heating the right foot of the wearer, as will more fully appear.

As here shown, the embodiment in Figure 1 also includes heating means, in the sleeve 51r, for the right arm, in this instance in two parts, one part 58a for the upper part of the arm and another part 58b for the lower part of the arm. The heating means 58a, 58b are in this instance connected in series and are fed by cable 60r comprising two conductors electrically connected to the bus conductor means 25 similarly to the cable 49r. The cables 49r and 60r are shown separated in Figure 1 for the sake of clearness, but they preferably lie side-by-side against the adjacent inside wall of the garment.

As here shown, the embodiment in Figure 1 also includes heating means for the right leg 55r, in this instance in two parts, one part 70a for the upper part of the leg and another part 70b for the lower part of the leg. The heating means 70a, 70b are in this instance connected in series and are fed by a cable 71r comprising two conductors electrically connected to the bus conductor means 25.

Means is provided for holding the hereinbefore mentioned cables in predetermined desired position within the garment, this means being here shown as a tape or elongated piece of fabric 61r disposed against the inside wall of the garment and stitched longitudinally at 62, 63 to the wall of the garment so as to form conduit means 64r in which the cables are disposed. The conduit means 64r is omitted in Figure 1 for the sake of clearness. The upper part 64a (Figure 3) of the conduit means 64r extends upwardly from the location of the belt means 20, around the arm pit part of the right hand sleeve 51r and downwardly a desired distance along the inside surface of the right hand sleeve. The conduit part 64a contains the cables 49r, 60r. The lower part 64b of the conduit means 64 extends downwardly from the location of the belt means 20, along the inside of the right hand leg 55r a desired distance. The conduit part 64b contains the cables 54r, 71r. The heating means for the left side that is for the left leg 55l and foot and the left arm 51l and hand is here shown the same as for the right side hereinbefore described, the heating means having

the same relative locations and being fed by cables 49_r, 60_r, and 54_r, 71_r, from the bus conductor means 25, and disposed in conduits as already described in connection with the cables 49_r, 60_r and 54_r, 71_r. If desired the cable 42 for feeding the heating means 37 may also be run in a fabric conduit 80 similar to the fabric conduit 64.

The heating means for the arms and legs may be constructed in the form of heating pads similarly to the heating means 37, and snap fasteners (not shown) may be used to detachably fasten the arm and leg pads to the garment. The arm and leg pads need not be made in two parts but each limb may be heated by a unitary pad.

Referring particularly to Figures 4 and 5 there is here shown an innersole means 90₇ comprising two pieces of leather 91, 92, or other suitable material, which are spaced apart by a member 93 of cork composition, or any other suitable material, having an aperture 94 which may generally follow the outline of the insole means 90₇, leaving a space in which is disposed an insulated resistor 95₇ having lead terminals 96 connected respectively to parts of snap fasteners 97 adapted to cooperate with the complementary snap fastener parts 57 carried by the cables 54_r and 54_l, respectively. The snap fasteners 97 are carried by a flexible tab 98 of suitable length made of two pieces of soft leather, or other suitable flexible insulating material, suitably stitched or otherwise fastened together and to the innersole means proper. Between the parts of the tab 98 are disposed the lead terminals 96 of the resistor 95₇. The resistor 95₇ may be suitably cemented in place. The pieces 91, 93, 92 may be cemented and stitched together.

The innersole means 90₇ is so constructed and arranged that it may be readily inserted into the left shoe (not shown) of a wearer of the garment, the tab 98 extending upwardly along the inside rear wall of the shoe, whereupon the wearer puts the shoe on his foot and snaps the connectors 97 to the connectors 57 on the cable 54_r or the cable 54_l as the case may be, it being of course understood that an innersole means similar to the innersole means 90₇ is provided for the right shoe of the wearer. It will be evident that if the resistor of an innersole means should fail or the innersole means should otherwise become unusable, it is not necessary to discard any shoe with which the innersole means is intended to be used. If desired the respective innersole means 90 may be inserted into over-foot-wear such as boots or over-shoes (not shown) which are adapted to be worn over the usual shoes, and in this case the innersole means will be disposed between the insole of the boot or over-shoe and the bottom of the sole of the usual shoe.

Referring now to Figures 7 and 8 there is here shown a mitten or glove 99₇ comprising in this instance a portion 100 adapted to take the thumb, a forefinger portion 101, and a portion 102 for the remaining three fingers. The portions 100, 101, 102 are heated by an insulated resistor 130₇ comprising insulated resistors 103, 104, 105 for the respective portions, these resistors being connected in series, the lead terminals 106, 107 to this series of resistors being connected to two snap fastener parts 108, 109 respectively, which are mounted on the inside of the mitten and are carried by a relatively stiff strip 110 of any suitable insulating material fastened to the glove as by screws and nuts 111 or in any other suitable way. A thermostat 112 may be interposed in the circuit of the resistors in order to interrupt the

circuit in response to excessive temperature. Ordinarily the desired rate of heat dissipation is higher for the resistors in the mitten than for others of the heating elements, so that excessive heating is more apt to occur.

Figure 8 shows a section of the portion 102 of the mitten of Figure 7, enlarged, the outer part 113 of the mitten being leather or other suitable material, lined with a wool layer or other suitable layer of material 114 which may if desired be cemented to the inside of the leather. The resistors 103, 104 and 105 are fastened between two layers of wool 115, 116 or other suitable material, shaped to conform to the inside of the layer 114, and desirably so constructed and arranged that the resistors and the covering layers 115, 116 constitute a unitary heating means separable from the mitten proper, so that if a resistor should fail, or the unit otherwise wear out, it is unnecessary to throw away the mitten proper.

The snap fastener parts 108, 109 of each mitten are adapted to cooperate with the complementary snap fastener parts 52 (Figure 1).

Referring now to Figure 10, there is here shown an electrical diagram of an embodiment suitable for use in case the garment comprises separate coat and trousers, as distinguished from a coverall type of garment. In this instance the belt of the trousers may contain bus conductor means 250 corresponding to the bus conductor means 25 of Figure 9. In this instance the bus conductor means has connected thereto a socket 140 into which may be inserted a plug carried by a cable (not shown) connected to or connectible to a source of electricity. In this respect the form shown in Figure 10 is the reverse of the form shown in Figure 9, and, of course, if desired, the form shown in Figure 10 may embody a cable such as the cable 27 of Figure 9, having a plug 28 connectible to a source of electricity.

The bus conductor means has connected thereto a socket 350, corresponding to the socket 35 of Figure 9 but having an additional function as will appear. Auxiliary bus conductor means 250a is provided which is carried by the coat part of the garment. The auxiliary bus conductor means 250a has connected thereto a cable 150 of suitable length so that a plug 151 carried at the end of the cable may be plugged into the socket 350 so that the bus conductor means 250a is fed in parallel with the bus conductor means 250 from the socket 140 through a switch 340 corresponding to the switch 34. The auxiliary bus conductor means 250a is adapted to feed all of the heating means associated with the upper garment or coat, including the hands of the wearer, whereas the bus conductor means 250 is adapted to feed all of the heating means associated with the lower garment or trousers, including the feet of the wearer. The cables in Figure 10 corresponding to those in Figure 9 bear reference characters in which the numerals of the reference characters of Figure 9 have been multiplied by ten, for example, cable 490_r of Figure 10 corresponds to cable 49_r of Figure 9, and so on. It will be understood that the respective cables in Figure 10 lead to heating means corresponding to the heating means to which corresponding cables lead in Figure 9.

Referring again to Figure 9, the socket 35 may be used to receive a plug connected to conductor means leading to a heating pad, which may be a separate heating pad, on which the wearer of the garment may sit, or the socket may be used to make connection to an electric light, or to any other desired electric translating device. The

socket 350 of Figure 10 may be used for similar purposes, in which case the plug 151 will of course have been first removed.

By making the heating means for different parts of the body (which includes the limbs and extremities thereof) separate and connectible in parallel to the source of current (specifically the bus conductor means) each separate heating means has the same voltage applied thereto and each is designed to have a desired total heat dissipating capacity and a desired heat dissipating capacity per unit of area of the part of the body to which the respective heating means is applied. Obviously, the total rated heat dissipating capacity of a given heating mean, or the dissipating capacity per unit of applied area thereof, or both of these characteristics, may be made the same or different from these characteristics of one or more of the other heating means. Furthermore, greater flexibility of design is possible, particularly where, as is usually the case with respect to garments for aviators and so forth, the available voltage is relatively low, as for example of the order of 12 volts to 24 volts. Obviously, different sizes and/or lengths of resistor may be used, if desired or necessary, in the separate heating means.

Preferably the resistors of the heating means are made of material that has a high temperature coefficient of resistance, so as automatically to limit the current flow therethrough and hence the amount of heat generated, as the temperature of the heating means rises.

While the insulation for the resistors of the heating means may be of any suitable nature, such an insulated resistor as disclosed in the patent to Van Daam and Stranszky 2,251,697, August 5, 1941 is very desirably embodied in the various heating means hereinbefore described due to its moisture-resistant, heat-resistant and other mechanical and electrical characteristics.

From the foregoing it will be apparent to those skilled in the art that each of the illustrated embodiments of the invention provides new and improved electrically heated wearing apparel and accordingly, each accomplishes the principal object of my invention. On the other hand, it also will be obvious to those skilled in the art that the illustrated embodiments of my invention may be variously changed and modified, or features thereof, singly or collectively, embodied in other combinations than those illustrated, without departing from the spirit of my invention, or sacrificing all of the advantages thereof, and that accordingly, the disclosure herein is illustrative only, and my invention is not limited thereto.

I claim:

1. In combination: a garment; a plurality of individual electric heating means for heating different parts of the body of a wearer of said garment; individual conductor means for separately supplying each of said electric heaters with electric current; belt means, permanently fastened to said garment about the waist portion thereof, so constructed and arranged as to provide conduit means between the inside surface of said belt means and the outside surface of said waist portion; bus conductor means disposed in said conduit means; electrical connection means, electrically connected to said bus conductor means, constructed and arranged for connection to a source of electric current, to connect said source to said bus conductor means; said individual conductor means being electrically fixedly connected to said bus conductor means; and switch means

carried by said belt means and electrically interposed in said bus conductor means for controlling the supply of current to said bus conductor means separately from said electrical connection means.

2. In combination: a garment; a plurality of individual electric heating means for heating different parts of the body of a wearer of said garment; individual conductor means for separately supplying each of said electric heating means with electric current; belt means, permanently fastened to said garment about the waist portion thereof, so constructed and arranged as to provide conduit means between the inside surface of said belt means and the outside surface of said waist portion; bus conductor means disposed in said conduit means; electrical connection means, electrically connected to said bus conductor means, constructed and arranged for connection to a source of electric current, to connect said source to said bus conductor means; said individual conductor means being electrically fixedly connected to said bus conductor means; and electrical outlet means, carried by said belt means and electrically connected to said bus conductor means, constructed and arranged for connection to a source of electric current, to connect said source to said bus conductor means; said individual conductor means being electrically fixedly connected to said bus conductor means; and electrical outlet means, carried by said belt means and electrically connected to said bus conductor means, constructed and arranged for connection to a source of electric current, to connect said source to said bus conductor means.

3. In combination: a garment comprising a part constructed and arranged to encircle a portion of the body of a wearer of said garment, said part being discontinuous at one place in the direction of encirclement, the free ends at said place being provided with joining means for detachably joining said ends, the circumferential extent of said part being such that when said joining means joins said ends, said part loosely encircles said portion of the body of a wearer; electric heating means carried by and on the inside of said part of said garment, said heating means being of less circumferential extent than said garment part and constructed and arranged to engage said portion of the body of the wearer when said joining means joins said ends; and said heating means and said part of said garment being relatively so constructed and arranged that said heating means is pressed into heat-conducting relation to said portion of the body of the wearer by reason of circumferential tension on said heating means caused by joining of said ends by said joining means, while joining of said ends leaves said garment part free of circumferential tension and loosely encircling said heating means.

4. In combination: a garment comprising a part constructed and arranged to encircle a portion of the body of a wearer of said garment, said part being discontinuous at one place in the direction of encirclement, the free ends at said place being provided with joining means for detachably joining said ends, the circumferential extent of said part being such that when said joining means joins said ends, said part loosely encircles said portion of the body of a wearer; electric heating means carried by and on the inside of said part of said garment, said heating means being a belt-like unit of less circumferential extent than said garment part and constructed and arranged to engage said portion of the body of the wearer when said joining means joins said ends; and said heating means and said part of said garment being relatively so constructed and arranged that said heating means is pressed into heat-conducting relation to said

portion of the body of the wearer by reason of circumferential tension on said heating means caused by joining of said ends by said joining means, while joining of said ends leaves said garment part free of circumferential tension and loosely encircling said belt-like heating means.

5. In combination: a garment comprising a part constructed and arranged to encircle the torso of a wearer of said garment, said part being discontinuous at one place in the direction of encirclement, the free ends at said place being provided with joining means for detachably joining said ends, the circumferential extent of said part being such that when said joining means joins said ends, said part loosely encircles the torso of a wearer; electric heating means carried by and on the inside of said part of said garment, said heating means being a belt-like unit of less circumferential extent than said garment part and constructed and arranged to engage the torso of the wearer when said joining means joins said ends; means for fastening the ends of said belt-like unit to the inside of said garment near the parts of said joining means respectively; and said heating means and said fastening means of said garment being relatively so constructed and arranged that said heating means is pressed into heat-conducting relation to the torso of the wearer by reason of circumferential tension on

5

said heating means caused by joining of said ends by said joining means, while joining of said ends leaves said garment part free of circumferential tension and loosely encircling said belt-like heating means.

10 5 GERRIT VAN DAAM.
